(57) **CLAIM**

The ornamental design for a wristband as shown and described.

DESCRIPTION

FIG. 1 is a front view of a first embodiment of a wristband showing my new design.

FIG. 2 is a rear view of the wristband shown in FIG. 1.

FIG. 3 is a front perspective view from the knot-end of the wristband shown in FIG. 1.

FIG. 4 is a front perspective view from the other end of the wristband shown in FIG. 1.

FIG. 5 is a first side elevation view of the wristband shown in FIG. 1.

FIG. 6 is a second side view of the wristband shown in FIG. 1.

FIG. 7 is a front view of a second embodiment of a wristband of my new design.

FIG. 8 is a side view (of the knotted side) of the wristband shown in FIG. 7.

FIG. 9 is a second side view (of the knot-less side) of the wristband shown in FIG. 7.

FIG. 10 is a rear view of the wristband shown in FIG. 7.

FIG. 11 is a front view of a third embodiment of a wristband of my new design.

FIG. 12 is a first side view of the wristband shown in FIG. 11.

FIG. 13 is a second side view of the wristband shown in FIG. 11.

FIG. 14 is a rear view of the wristband shown in FIG. 11.

FIG. 15 is a front view of a fourth embodiment of a wristband of my new design.

FIG. 16 is a first side view of the wristband shown in FIG. 15.

FIG. 17 is a second side view of the wristband shown in FIG. 15; and,

FIG. 18 is a rear view of the wristband shown in FIG. 15.

The dash-dash broken lines showing a hand and a label with the text Bandit illustrate environmental structure; the dash-dash broken lines showing a wristband and Charm illustrate
